E. A. BOND

RESERVE FUEL SUPPLY TANK

Filed May 9, 1925

Inventor

E. A. Bond

By

Alanson C. Davis

Attorney

UNITED STATES PATENT OFFICE.

EDGAR A. BOND, OF RAMAH, NEW MEXICO.

RESERVE-FUEL-SUPPLY TANK.

Application filed May 9, 1925. Serial No. 29,131.

To all whom it may concern:

Be it known that I, EDGAR A. BOND, a citizen of the United States, residing at Ramah, in the county of McKinley and 5 State of New Mexico, have invented certain new and useful Improvements in a Reserve-Fuel-Supply Tank, of which the following is a specification.

This invention relates to improvements in 10 fuel feeding devices for automobiles, and has for its principal object to provide a reserve supply for use in case of an emergency when the fuel in the main tank has been entirely consumed.

15 One of the important objects of the present invention is to provide a reserve supply tank which communicates with the main supply tank, the former being filled simultaneously with the filling of the main 20 tank, means being provided whereby the fuel in the main tank will be entirely consumed before fuel in the reserve or auxiliary supply tank can be obtained.

25 A further object is to provide a reserve supply tank which includes a fitting, the latter having communication with the carburetor of the internal combustion engine of the automobile, means being further provided whereby the fitting communicates with 30 the main tank, an additional means being provided whereby the fuel in the auxiliary or reserve tank may be discharged therefrom through said tank into the supply pipe extending to the carburetor.

35 A further object is to provide a device of the above mentioned character which is simple in construction, inexpensive, strong and durable, and further well adapted to the purpose for which it is designed.

40 Other objects and advantages of this invention will become apparent during the course of the following description.

In the accompanying drawing forming a 45 part of this application, and in which like numerals designate like parts throughout the same:

Figure 1 is a sectional view through the auxiliary tank and the fitting associated therewith showing the relation thereof with 50 reference to the bottom of a main fuel supply tank, and

Figure 2 is an end elevation of the auxiliary tank and the fitting.

In the drawing, wherein for the purpose 55 of illustration is shown the preferred embodiment of my invention, the numeral 1

designates the bottom portion of a fuel tank such as is commonly provided on automobiles and for the purposes of the present invention, I designate the same as a main fuel 60 supply tank. Disposed below the main fuel supply tank is the reserve or auxiliary supply tank 2. Communication between the aforementioned tanks is afforded through the medium of the short piece of pipe 3, the 65 upper end of which is threaded into an internally threaded flange 4 which extends around the opening 5 provided in the bottom of the main tank. The lower end of the pipe 3 is also threaded in a similar internally threaded flange 6 which is disposed 70 around the opening 7 formed in the top of the reserve or auxiliary tank 2. This construction is more clearly illustrated in 75 Figure 1.

An opening 8 is formed in the bottom of the auxiliary or reserve tank 2 in registry with the opening 7 and an internally threaded flange 9 surrounds the opening 8, and is disposed on the bottom of the auxiliary tank. A fitting designated generally 80 by the numeral 10 has its upper end externally threaded, and threaded into the internally threaded flange 9 whereby the same depends from and is supported by the auxiliary or reserve fuel supply tank 2. The fitting is provided with a chamber 11 in the lower portion thereof. A fuel discharge pipe 12 extends from the side of the fitting 10, and communicates with the upper portion 85 of the chamber 11 by the coupling 13. The pipe 12 is adapted to extend to the carburetor of the automobile, not shown, in the usual manner.

The fitting 10 is further provided with 90 the vertical passages 14 and 15 respectively, the same affording a communication between the auxiliary tank 2, and the chamber 11. The upper portion of the fitting is further provided with a transversely extending 95 conical bore 16 in which is seated the rotary valve 17, the latter being also substantially conical shaped. The valve 17 is provided with the transversely extending passages 18 and 19 respectively, the same being disposed in right angles with respect to each other, and the purpose thereof will herein-after be more fully described. A suitable handle 20 is associated with the rotary valve 100 for facilitating the actuation thereof.

A short piece of tubing 21 has its lower 105 end externally threaded and threaded into

the upper of the vertical passage 14. This short piece of tubing extends upwardly within the auxiliary tank 2, and the upper end thereof extends into the lower end of 5 the short piece of pipe 3, as is clearly illustrated in Figure 1 of the drawing, and the purpose of this arrangement will also hereinafter be more fully described.

10 A pet cock 22 is provided at the bottom of the fitting 10, and has communication with the chamber 11 for the purposes of the chamber to be drained and the sediment removed therefrom whenever it becomes necessary.

15 Normally, when the parts are arranged as shown in Figure 1 of the drawing, it is obvious that when the main fuel tank 1 is filled, the auxiliary tank will also be simultaneously filled. With the valve 17 disposed in the manner as illustrated whereby the port or passage 18 is in communication with the passage 14 and the part 19 is out of communication with the passage 15, fuel from the main tank 1 will be adapted 20 to flow into the chamber 11 and out through the discharge pipe 12 to the carburetor for the usual consumption by the engine. The short piece of tubing 21 affords a means whereby the fuel from the main tank will 25 be delivered to the chamber 11 of the fitting 10.

When the main supply tank 1 becomes empty, and there is no possibility of any fuel entering the chamber 11 through the 30 short piece of tubing 21, and the passage 14 of the fitting when the port 18 of the valve 17 is in registry therewith, the valve is rotated by actuating the handle 20 so that the port 18 is brought out of alignment or registry with the passage 14 and simultaneously causing the port of the valve 17 to be in alignment or registry with the passage 15. When the parts are arranged as thus described, the fuel in the reserve or 35 auxiliary supply tank 2 will be discharged therefrom into the chamber 11 and enable the automobile to be operated so that operator may reach the filling station which is located thereby in order that the main 40 fuel supply tank may be refilled. It is of course to be understood that the auxiliary tank will only hold about one gallon gas which is sufficient enough to permit the further operation of an automobile in case 45 of an emergency, the fuel in the main supply tank having been entirely consumed.

It will thus be seen from the foregoing 50 description, that a fuel feeding device has been provided which will at all times be positive and efficient in carrying out the purposes for which it is designed, and the simplicity in which the present device is constructed enables the same to be readily and easily attached to fuel supply tanks now 55 provided on automobiles of various makes.

While I have shown the preferred embodiment of my invention, it is to be understood that minor changes coming within the scope of the invention may be resorted to without departing from the spirit of the invention or the scope of the appended claims. 70

Having thus described the invention, what I claim as new and desire to secure by Letters Patent is:—

1. In combination with a main fuel supply tank, a reserve supply tank communicating therewith, a fitting associated with said reserve tank, said fitting being provided with a fuel chamber, a discharge pipe extending therefrom, said fitting being 75 provided with a pair of passages communicating at their lower ends with the chamber, one of said passages communicating at its upper end with the main fuel supply tank, the other passage communicating at 80 its upper end with the reserve supply tank, and means associated with the fitting and said passages for effecting the excommunication of one of the passages with said chamber. 85

2. In combination with a main fuel supply tank, a reserve supply tank communicating therewith, a fitting associated with said reserve tank, said fitting being provided with a fuel chamber, a discharge pipe extending therefrom, said fitting being 90 provided with a pair of passages communicating at their lower ends with the chamber, one of said passages communicating at its upper end with the main fuel supply tank, the other passage communicating at its upper end with the reserve supply tank, means associated with the fitting and said 95 passages for effecting the excommunication of one of the passages with said chamber, said means comprising a rotary valve supported transversely in the fitting, the valve being provided with a pair of ports disposed at right angles with respect to each other and adapted for cooperation with the respective 100 105 passages. 110

3. In combination with a main fuel supply tank, a reserve supply tank communicating therewith, a fitting associated with the reserve tank, said fitting being provided with a fuel chamber, a discharge pipe extending therefrom, said fitting being further provided with a pair of vertical passages communicating at their lower ends with the fuel chamber, the upper end of one of the passages communicating with the reserve supply tank, a tube supported at its lower end in the upper end of the other passage and extending upwardly through the reserve tank and communicating at its upper end with the main tank, a rotary valve supported transversely in the fitting, said valve being provided with a pair of ports disposed at right angles with respect to each other, each of said ports 115 120 125 130

adapted for registration with the respective passages.

4. In combination with a main fuel supply tank having an opening in the bottom thereof, a reserve supply tank disposed below the main tank and being provided with an opening in the top thereof, a pipe disposed in said openings and affording a communication between the main tank and the 10 reserve tank, a fitting associated with the bottom of the reserve tank, said fitting being provided with a fuel chamber, a discharge pipe extending therefrom, said fitting being further provided with a pair of 15 vertical passages communicating at their

lower ends with the fuel chamber, a piece of tubing supported at its lower end in the upper end of one of the passages and extending upwardly through the reserve tank, the upper end of the tubing extending into 20 the lower portion of said pipe, the other passage communicating at its upper end with the reserve supply tank, and means associated with the fitting and cooperating with the passages for effecting the excommunication of either of the passages with the fuel chamber. 25

In testimony whereof I affix my signature.

EDGAR A. BOND.
